By

J. Keam Killen, attorney

UNITED STATES PATENT OFFICE.

WILLIAM WHITE, OF WHITE PIGEON, MICHIGAN, ASSIGNOR TO BENJAMIN O. WADE,
OF WHITE PIGEON, MICHIGAN.

WRENCH.

Application filed June 15, 1921, Serial No. 477,658. Renewed June 19, 1924.

This invention relates to an improved wrench, and more particularly to a wrench that may be manipulated within a very narrow radius and which is especially adapted for use by automobile mechanics.

A further object of the invention is to provide a wrench of the above character which may be used for removing or replacing never-slip horseshoe calks.

10 A still further object of the invention is to provide a device as above described consisting of but a few parts and one which it is believed may be manufactured at a very low cost.

15 Various other objects and advantages of my invention will become apparent during the continuance of the following description.

In the drawings:—

Fig. 1 is a view and side elevation showing my invention as in its preferred embodiment,

Fig. 2 is a view in perspective of one element or section of my invention, and

Fig. 3 is a view in perspective of the other element or section of the wrench.

In describing my invention more in detail, 11 and 10 designate the main elements of the wrench, each of which consists of a handle portion 12 and 13, and intermediate portion 14 and 15 and a jaw or gripping portion 16 and 17. Each element may be cast in a separate integral piece and afterwards machined (if necessary) into final form.

The intermediate portion of the element 10 15 joins one end of the handle 13 and lies in a plane at a substantially 60-degree angle with respect thereto, terminating in the jaw 17. In order to increase the effectiveness of the wrench the jaw 17 extends at a substantially 45-degree angle from the intermediate portion 15 and at a substantially 60-degree angle with respect to the longitudinal axis of the handle 13. The intermediate portion 15 is provided with an opening 18 for the reception of a pivot member hereinafter described, while the inner or engaging face of the jaw 17 is corrugated or notched as at 19.

Upon reference to Fig. 3 it will be observed that the jaw 17 is substantially twice as thick as the intermediate portion 15 and the handle portion 13, thus providing an up-

standing shoulder 20 at its rear end and at the front end of the intermediate portion 15 for the purpose that will presently appear.

The intermediate portion 14 of the element 11 extends at a substantially 60-degree angle from the handle portion 12 and terminates in the jaw 16 that is curved in substantially the arc of a circle. The jaw 16 also extends at a substantially 45-degree angle with respect to the intermediate portion 14 and has its inner or engaging face corrugated or notched as at 21 with inwardly and hookedly projecting teeth. I further provide the intermediate portion 14 with an opening 22, 65 which, when the elements are assembled, is aligned with the opening 18 of the element 10 and through which is positioned a pivot member 23' which retains the elements in operative pivotal relation. 70

Like the jaw 17, the jaw 16 is substantially twice the thickness of the intermediate portion 14 and the handle portion 12 so as to form a shoulder 23 at its rear end and at the front end of the intermediate portion 14. 75 Consequently when the elements are assembled as shown in Fig. 1, the combined thicknesses of the two intermediate portions and handle portions equals the thickness of each of the jaws, thus presenting a device 80 having a substantially regular contour. The intermediate portions 14 and 15 are, moreover, provided with convex bearing edges 24 and 24', respectively, which are engaged by the concave faces of the said shoulders 20 and 85 23 of the jaws; the said engaged bearing faces of the said shoulders and edges respectively being adapted for relatively sliding contact during the opening and closing movement of the said jaws. 90

When assembled as shown in Fig. 1, the wrench may be easily and quickly manipulated and owing to the curved engaging face of the jaw 16 and the substantially straight engaging face of the jaw 17, it may be engaged with and used to advantage in connection with the removal of nuts, bolts, and the like which are of varying thicknesses and diameters. 95

By reason of the novel and peculiar arrangement of the engaging faces of the jaws it will also be observed that the wrench may 100

be used to advantage in connection with never-slip horseshoe calks and the like devices.

From the foregoing it is believed that the 5 advantages and novel features of my invention will be readily understood and therefore further detailed description is deemed unnecessary.

The lower jaw 16 is in the outer position 10 in relation to the pivot center, and the shorter jaws 17 is in the inner position and relation of said jaws. This relation is of importance in that the pull of the handle causes the outer jaw with its inwardly hooking teeth to 15 effectively engage with very slight pressure from the co-operating inner jaw, and presents a comparatively broad curved surface in contact with a pipe or other object being turned. This outer and inner relation is 20 of importance to secure the effective co-operation of the parts when they are manipulated.

From the description it will be seen that the handles are in side by side relation and 25 of equal length and consequently come into the hand of the user in such manner that they can be readily and independently manipulated and opened and closed, thereby controlling the action of the jaws to secure 30 very strong or very gentle action of the grip-

ping teeth, as the work in hand may require.

Having thus fully described by invention what I claim as new and desire to secure by Letters Patent is:—

What is claimed is:

A wrench comprising a pair of pivotally connected complementary members, each of which embodies a flat vertically disposed handle portion, a jaw portion inclined to the axis of the handle, and an integral connecting portion between the said handle and jaw portions and lying in the plane of the said handle, the said connecting portions each oblique to the said jaw portions respectively with respect to the handle, the jaws of the 40 said members being of unequal length with respect to their respective gripping surfaces, the outer jaw being provided with inwardly-projecting serrations and the inner jaw with outwardly-projecting serrations, whereby 45 the outer jaw extends forwardly over and beyond the inner jaw, both said jaws being provided with shoulders at the connecting portions, the said connecting portions being adapted for relative sliding movement during the opening and closing movement of the 50 said jaws.

In testimony whereof I affix my signature.

WILLIAM WHITE.
